UNITED STATES PATENT OFFICE

128,406

DESIGN FOR A RECEPTACLE FOR RECEIVING AND STORING BLOOD

Abe Soontup, New York, N. Y., and John E. B. Swabacker, Chicago, Ill.

Application December 28, 1940, Serial No. 97,682

Term of patent 7 years

To all whom it may concern:

Be it known that we, Abe Soontup and John E. B. Swabacker, citizens of the United States, residing, respectively, at New York, in the county of New York and State of New York, and at Chicago, in the county of Cook and State of Illinois, have jointly invented a new, original, and ornamental Design for a Receptacle for Receiving and Storing Blood, of which the following is a specification, reference being had to the accompanying drawing, forming part thereof.

Fig. 1 is a perspective view, Fig. 2 is a top plan view and Fig. 3 is a direct elevational view of a receptacle for receiving and storing blood showing our new design.

The characteristic features of our design reside in the combination on the specific bottle disclosed of a screw cap having on the recessed top portion thereof a relatively small cylindrical upstanding member from which a narrow close-fitting tab extends to the outer edge of said cap and continues downwardly over a part of the threaded section thereof, all as shown.

We claim:

The ornamental design for a receptacle for receiving and storing blood, substantially as shown and described.

ABE SOONTUP.
JOHN E. B. SWABACKER.
